William Anderson of New York City
Lettors-Patent.

The Schedule contained in these Letters Patent and making part of the same contains
 my description in the words of the said William Anderson himself of his improvement
 in the mode of constructing Parlor and other grates.

To all whom it may concern. To be it known that I William Anderson
 of the City of New York in the State of New York have invented an improved mode
 of constructing Parlor and other grates in which anthracite or other fuel is burnt
 in which improved grate stones or fire place the heat from the fuel is economized by
 the employment of reflectors which form or cover the joints, and the inclined front
 of the opening of the格栅 or fire place above the throat thereof, and do hereby de-
 clare that the following is a full and exact description thereof reference being had
 to the drawing which accompanies and makes a part of this Specification.

This Grate with its reflectors may be placed within an open fire, constructed
 in the manner of that generally called the Franklin Stove, having a pipe
 or opening on the back or left side of leading into a chimney or fire place thus allowing
 the same to stand and from a fire box or Hall or oil may be placed within
 and is now of the fire place built or standing within an ordinary fire place.

Fig. 1. in the accompanying drawing represents a cast iron front, joints, & back
 of a fire place. The flat plates A are intended to fit up against the ordinary front
 of a fire place so that the joints B.B. and the inclined back or upper plate
 C in front of the throat D shall stand adiuv. allowing the back C to touch or
 approach toward the back of the ordinary fire place. The plate C generally trends
 so that it may be raised or lowered as may be found convenient, which may be
 done by means of hooks or other contrivances. The joints B.B. I prefer to cast
 in the same form as being best adapted to the reflectors by which they are to be covered
 as the convex form of the reflectors side, it is believed to distribute the radiant heat more
 advantageously into the apartment. They may however be made flat or even concave
 to a certain extent and yet produce much of the benefit to be derived from the re-frac-
 tion of the radiant heat. The upper inclined plate C, inclines or inclines back
 from the front plate A to the throat or opening of the grating D. This plate C
 generally makes flat and cover it with a reflecting plate of the same form; but

the stove is preferred may be made convex or concave. Fig. C. represents the reflecting jamb, and top inclined plate which are intended to cover the cast iron or other jamb, and top plate in fig. 1. I have in the drawing represented the jamb, & top plate as in one piece, but I usually make them in three pieces being separated at the middle. A. B. They have thin edges prepared to receive them, and hold them in their places at the bottom of the jamb, B. B. fig. 1. and at their junction with the top plates C. When the Franklin Stove form is prepared, the whole arrangement receives the name with that already described, excepting that the pipe D. is connected with, and leads to the pipe which is to carry off the gases or products of combustion. Such a fire place or Stove may be very advantageously used for the purpose of cooking by those who wish to employ it in that way. A metallic box or case furnished with reflectors, or the inside may be made to stand up on the hearth, its edges fitting against the plates A. B. Metal hooks, pins, &c. may be placed within this and a portable jack may be used. Such a construction may be placed upon wheels, so as to be readily moved ^{up} & down to receive from any place towards the fire. The reflectors forming or covering the jamb, and inclined top plates may be made of any kind of metal which can readily be polished and kept bright. I have found sheet zinc to answer the purpose perfectly well and it is sufficiently firm and unyielding to admit of its being removed for cleaning without being liable to injury which is a point of considerable importance instead of reflectors of polished metal. I intend sometimes to use surfaces covered with enamel which may be easily cleaned and is also a good reflector of heat.

What I claim as my invention and wish to prevent by Letters Patent is the construction of the jamb and top plates of Stoves, grates or fire places by forming or covering them with polished reflectors substantially in the manner described whether the same be applied upon foundations of cast iron as herein set forth or upon any other material, or in any other manner in which similar results are obtained by analogous means.
